UNITED STATES PATENT OFFICE

133,502

DESIGN FOR A LOCOMOTIVE BODY

William D. Otter, Oak Park, Ill., and Paul A. Meyer, Detroit, Mich., assignors to General Motors Corporation, Detroit, Mich., a corporation of Delaware

Application June 4, 1942, Serial No. 107,103

Term of patent 14 years

To all whom it may concern:

Be it known that we, William D. Otter and Paul A. Meyer, citizens of the United States, William D. Otter being a resident of Oak Park, county of Cook, and State of Illinois, and Paul A. Meyer being a resident of Detroit, county of Wayne, and State of Michigan, have invented a new, original, and ornamental Design for Locomotive Body, of which the following is a specification, reference being made to the accompanying drawing forming a part thereof.

In the drawing:

Fig. 1 is a side elevational view of a locomotive body showing our design;

Fig. 2 is a perspective view of same, as seen from a point in front of and at the side of the body; and

Fig. 3 is a front elevational view thereof.

The appearance of the side of the body opposite to that shown is substantially the same as that shown, and the rear end portion of the locomotive body design is conventional.

We claim:

The ornamental design for a locomotive body, substantially as shown and described.

WILLIAM D. OTTER.
PAUL A. MEYER.
